UNITED STATES PATENT OFFICE.

GUY L. KLUEFER, OF CHICAGO, ILLINOIS, ASSIGNOR TO RICHARD J. COYNE, WILLIAM M. RETTIG, W. W. KLORE, AND N. ROGERS BARR, TRUSTEES FOR MULTI-X AIR-CRAFT & MOTORS COMPANY, OF CHICAGO, ILLINOIS, A CORPORATION OF DELAWARE.

PISTON-VALVE-CONTROLLING MEANS.

Application filed March 14, 1921. Serial No. 452,154.

To all whom it may concern:

Be it known that I, GUY L. KLUEFER, a citizen of the United States, residing at Chicago, in the county of Cook and State of Illinois, have invented certain new and useful Improvements in Piston-Valve-Controlling Means, of which the following is a specification.

This invention relates to improvements in piston valve controlling means particularly adapted though not necessarily limited in its use in that type of engine embodying a revolving cylinder and in which the piston valve is automatically unseated at predetermined points in the revolution of the cylinder:

More specifically, the invention relates to improved means for positively seating and holding the piston valve seated at predetermined points in the operation of the engine.

To the attainment of these ends, and the accomplishment of other new and useful objects as will appear, the invention consists in the features of novelty in substantially the construction, combination and arrangement of the several parts hereinafter more fully described and claimed and shown in the accompanying drawing illustrating this invention and in which—

Figure 1 is a view partly in elevation and partly in longitudinal section of a piston and the piston valve controlling means.

Figure 2 is a sectional view taken on line 2—2, Figure 1.

Figure 3 is a view of the blank for the valve controlling element.

Figure 4 is a perspective view of the valve controlling element.

Figure 5 is a top plan view of the piston with the valve removed.

Referring more particularly to the drawing the numeral 10 designates the head of the piston provided with a valve opening 11, therethrough having a valve seat 12, encompassing the opening. Detachably connected with the piston head preferably by means of screw threads 13, is a skirt or sleeve 14, constituting the body of the piston and the piston is provided with the usual packing rings 15.

A valve 16, co-operates with the opening 11 and is adapted to be seated upon the

valve seat 12. This valve is provided with the usual stem 17 passing through a suitable guide 18, in the piston head.

The numeral 19 designates generally a piston controlling element which is preferably constructed of a single piece of sheet material cut into shape so as to form surfaces 20 and oppositely disposed surfaces 21—22. The blank is also shaped to form arms 23, which are adapted to be bent or positioned so that the extremities of the arms 23, contact to form a portion 24, which is adapted to enter an opening in the valve stem 17, beneath the guide 18. This element is arranged within the hollow piston so that the portions 21 and 22 will have bearings against the wall of the piston so that the element will be guided in its reciprocating movement within the piston, by the piston wall.

Inasmuch as the skirt or portion 14, of the piston is detachably secured to the head 10, it will be manifest that the element 19, may be readily connected with the valve 16 by inserting the portion 24, of the element into the opening in the valve stem, after which the skirt or portion 15, may be attached to the head 10.

The piston is adapted to be reciprocated by means of a suitable piston rod 25, which is pivotally connected as at 26, with the piston and at such a point that the piston rod 25, will have an oscillatory movement with respect to the piston. The element 19 is so constructed that when it is placed in position within the piston, portions of the element will stand astride of the piston rod 25, and the piston rod is preferably provided with a projection 27, and lugs 28 project laterally from the projection 27. This projection 27, is so disposed that the lugs 28, will engage the surfaces 20 of the element 19.

As the piston is reciprocated, and the piston rod 25, is given a pivotal movement with respect thereto it will be manifest that inasmuch as the lugs or projections 28, engage the surfaces 20, the element 19, will be moved in one direction by the lugs at a predetermined point in the operation of the piston and this will move the element 19 in a direction to cause the valve 16 to engage 105 and rest upon the seat 12. The valve will

be held in this closed position until the piston rod 25, starts to move in the opposite direction and at which time the lugs or projections 28, will assume positions, during such movement of the piston rod, as to allow the valve 16 to be unseated, preferably by centrifugal force, this force exerted upon the valve will tend to unseat the valve and during this unseating movement the element 19 will be moved in the opposite direction so as to permit of a ready unseating of the valve.

Obviously the lugs 28, may be so disposed that the valve may be seated at any predetermined interval during the operation of the engine.

It is thought that the operation of this device will be clearly understood from the foregoing, but briefly stated it is as follows:

Assuming that the motor in which this piston and valve is placed is of a four cycle type and assuming further that the piston 14, is moving in a direction so as to take in a charge of fuel into the engine cylinder ahead of the piston, the valve 16 will be unseated as shown in Figure 1 and the parts will be in the position shown in the full lines and the piston will be substantially at the limit of its inward movement. With the charge in the cylinder, and upon the first movement of the piston towards the explosion end the valve will be closed and will cause a pressure to be exerted upon the charge and as the piston moves towards the explosion end to exert this pressure the piston rod 25, will move from the position shown in full lines in Figure 1, to the position shown in dotted lines. This will draw the valve 16 against the seat 12 and, as the charge is exploded, the pressure exerted upon the valve 16, will hold the same to its seat, even though the piston rod 25 moves in a direction so as to cause the projection 28, to move across the surface 20, in a direction to release the element 19. On the next stroke of the piston towards the explosion end of the cylinder, the burnt gases will be discharged in the ordinary manner. Upon the return of the piston the valve 16 will be released by the movement of the piston rod 25, and projection 28, so that the suction in the cylinder together with the centrifugal force will unseat the valve and a charge of fuel will be drawn into the explosion end of the cylinder and the valve will be seated by the movement of the projection 28 across the surface 20 to shift the element 19. Upon the next inward movement of the piston, although the valve will be released, it will not be unseated because it will be held to its seat by the pressure of the gases behind the valve.

With this improved construction it will be manifest that there is provided a means

for positively seating the valve and for holding the same to its seat at predetermined intervals in the operation of the piston.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A piston, a valve therein, a piston rod pivotally connected with the piston, a reciprocating element detached from the piston and connected with the valve, and means connected with the piston rod and adapted to engage and move the said element in one direction during a predetermined portion of the movement of the piston rod with respect to the piston, to close the said valve.

2. A piston, a valve therein, a piston rod pivotally connected with the piston, a reciprocating element connected with the valve, and means connected with the piston rod and adapted to engage and move the said element in one direction during a predetermined portion of the movement of the piston rod with respect to the piston, to close the said valve, the said element being detached from the piston and housed therein, said element being guided in its movement by the wall of the piston.

3. A hollow piston, a valve therein, a piston rod pivotally connected with the piston, a guide for the valve, a reciprocable element within the piston and connected with the valve, said element being detached from the piston, portions of said element engaging the wall of the piston to be guided thereby, and a shoulder on the piston rod engaging and moving across a portion of the said element for moving the element in one direction to close the valve.

4. A hollow piston, a valve therein, a piston rod pivotally connected with the piston, a guide for the valve, a reciprocable element within the piston and connected with the valve, said element being detached from the piston, portions of said element engaging the wall of the piston to be guided thereby, and a shoulder on the piston rod engaging and moving across a portion of the said element for moving the element in one direction to close the valve and maintain the same closed during a predetermined interval in the operation of the piston.

5. A hollow piston, a valve therein, a piston rod pivotally connected with the piston, a guide for the valve, a reciprocable element detached from and housed within the piston and detachably connected with the valve, portions of the element engaging the wall of the piston and being guided thereby, and a projection on the piston rod,

the said element having an extended surface arranged within the path of movement of the said projection, said projection engaging and moving across the said surface to shift the element in one direction to close the valve.

6. A hollow piston, a valve therein, a piston rod pivotally connected with the piston, a guide for the valve, a reciprocable element detached from and housed within the piston and detachably connected with the valve, portions of the element engaging the wall of the piston and being guided thereby, and a projection on the piston rod, the said element having an extended surface arranged within the path of movement of the said projection, said projection engaging and moving across the said surface to shift the element in one direction to close the valve, the said valve being unseated by centrifugal force and operating to shift the said element in the opposite direction when the said projection moves in another direction across said surface.

7. A hollow piston, a valve therein, a piston rod pivotally connected with the piston, a guide for the valve, a reciprocable element housed within the piston and connected with the valve, said element being formed of sheet material and shaped to form an arm detachably connected with the valve and spaced guiding portions movable against the piston wall, said element having a surface extending in a direction across the piston, and a projection on the piston rod engaging and moving across said surface to shift the said element in one direction to close the valve.

8. A hollow piston, a valve therein, a piston rod pivotally connected with the piston, a guide for the valve, a reciprocable element housed within the piston and connected with the valve, said element being formed of sheet material and shaped to form an arm detachably connected with the valve and spaced guiding portions movable against the piston wall, said element having a surface extending in a direction across the piston, and a projection on the piston rod engaging and moving across said surface to shift the said element in one direction to close the valve, the piston wall and the said guiding portions of the said element also serving to maintain the said element and valve against detachment.

9. A hollow piston, a valve therein, a piston rod pivotally connected with the piston, a guide for the valve, a reciprocable element housed within the piston and connected with the valve, said element being formed of sheet material and shaped to form an arm detachably connected with the valve and spaced guiding portions movable against the piston wall, said element having a surface extending in a direction across the piston, and a projection on the piston rod engaging and moving across said surface to shift the said element in one direction to close the valve, portions of the said element being disposed on opposite sides of the piston rod.

In testimony whereof I have signed my name to this specification on this 9th day of March, A. D. 1921.

GUY L. KLUEFER.
